SPACE RESONANT SYSTEM

Elmer D. McArthur, Schenectady, N. Y., assignor
to General Electric Company, a corporation of
New York

Application October 23, 1942, Serial No. 463,087

15 Claims. (Cl. 250—36)

1

My invention relates to space resonant systems and more particularly to ultra high frequency systems for the utilization and production of ultra high frequency energy.

It is an object of my invention to provide a new and improved ultra high frequency space resonant system.

It is another object of my invention to provide a new and improved ultra high frequency space resonant system comprising improved coupling means for interconnecting a plurality of space resonant regions.

It is a further object of my invention to provide a new and improved space resonant system comprising coupling means for interconnecting a plurality of space resonant regions and which is suitable for utilization in a system intended to operate over a wide range of frequency without entailing adjustment of the coupling means.

Briefly stated, in the illustrated embodiment of my invention I provide a new and improved ultra high frequency space resonant system which constitutes, as an energizing or control element of the system, an electric discharge device including a plurality of enclosed electrodes including an anode, a cathode and a grid and in which anode-grid and grid-cathode space resonant regions are defined by a plurality of conductive members which may be concentric. The intermediate member forming the common boundary between the two regions, or the member connected to the grid of the discharge device is provided with an opening positioned within the vicinity of the maximum of the anode-grid standing potential wave, thereby constituting a coupling or communicating path between the respective regions. This opening may have a configuration such that it has an appreciable axial or longitudinal dimension to permit adjustment of the operating frequency of the space resonant system as a whole, whereby the desired degree of coupling is obtained throughout the range of operating frequencies without necessitating adjustment of the coupling means. For example, the opening may have a helical configuration and is of such width that its presence will not materially disturb the desired wave transmitting and propagating characteristics of the respective regions, and at the same time affords the desired coupling.

For a better understanding of my invention, reference may be had to the following description taken in connection with the accompanying drawing, and its scope will be pointed out in the appended claims. Fig. 1 diagrammatically illus-

2

trates an embodiment of my invention as applied to a space resonant system including an electric discharge device and three concentric conductive or metallic cylinders connected to the electrodes of the discharge device, and wherein the coupling means constitutes a helical opening, or a pair of such openings, in the cylinder constituting the common boundary between the anode-grid and the grid-cathode regions. Fig. 2 is a detailed view of the discharge device employed in the arrangement of Fig. 1. Fig. 3 represents certain features of the space resonant system and the coupling opening or slot.

Referring to Fig. 1 of the accompanying drawing, my invention is there illustrated as applied to an ultra high frequency space resonant system which may include, as a control element thereof, an electric discharge device 1 which is associated with a plurality of metallic or conductive members which define a plurality of space resonant regions. Prior to the description of the space resonant system as an entirety, it is believed that reference may initially be had to Fig. 2 wherein the discharge device 1 is shown in more detail. The discharge device 1 includes a plurality of enclosed electrodes, such as a metallic cylindrical anode 2, a cylindrical cathode 3 having its emissive surface 4 facing the end of anode 2, and a grid 5 spaced between the anode 2 and cathode 3 and preferably lying in a plane spaced a small distance from the cathode emissive surface. The discharge device 1 is constructed preferably to have a generally stepwise configuration and constitutes a plurality of metallic members or discs 6, 7 and 8 which support anode 2, grid 5 and cathode 3, respectively. It will be observed that the diameters of discs 6—8 progressively increase to afford the above mentioned stepwise configuration. Disc 8 may be formed integral with a cylindrical skirt 9 which serves as a supporting or securing means between the elements of the discharge device and base 10. Discs 6, 7 and 8 are maintained in spaced relation with respect to each other by means of a pair of cylindrical insulating cylinders 11 and 12 which are sealed to the discs and constitute in part an enclosure for the electrodes of the discharge device.

Cathode 3 is provided with a flanged part 13 which parallels the under-surface of disc 8 and is spaced therefrom by means of an insulating member or washer 14. In this manner, the cathode 3 is electrostatically coupled to disc 8 but electrically insulated therefrom so far as direct currents are concerned. Unidirectional current or potential may be applied to cathode 3 by

means of conductors 15 and 16 which are terminated in contact pins 17 and 18 secured to base 10. Cathode heating element or coil 19 is provided with a pair of conductors 20 and 21 which are likewise terminated in contact pins 22 and 23 also secured to base 10. It will be appreciated, of course, that conductors 15, 16, 20 and 21 are sealed to a metallic header (not shown) located within the base 10, this header also being, of course, welded or soldered to the skirt 9 thereby completing the evacuated enclosure for the electrodes of the discharge device.

In order to afford a high frequency connection means for the discharge device, anode 2 may be provided with an enlarged section or part 24. It will be appreciated that the anode 2 and disc 6 are closely fitted in order to maintain the desired low pressure within the discharge device. The discharge device described above is the prior invention of James E. Beggs and is described and claimed in his copending application, Serial No. 436,633, filed March 28, 1942, and assigned to the assignee of this invention.

Referring again to Fig. 1, I employ means in conjunction with the discharge device 1 for defining a plurality of space resonant regions. More particularly, in one form of my invention the space resonant regions may be defined in part by a plurality of substantially concentric metallic or conductive cylinders 25, 26 and 27. Cylinders 25 and 26 define the anode-grid space resonant region, and cylinders 26 and 27 define the grid-cathode space resonant region. Cylinder 26 may be connected to disc 7 of the discharge device 1 through adapting means, such as a resilient annular member 28 of conductive character, to afford a suitable high frequency connection thereto, and a disc 8 may be connected to cylinder 27 through an annular member 29 of metallic construction which may be secured rigidly to cylinder 27 by being attached to a metallic ring 30 closely fitting to the inner surface of cylinder 27. The combination of an electric discharge device having transverse disk-like terminals and concentric resonators, is described and claimed in the copending Jensen and Keister application 448,206, filed June 24, 1942, and assigned to the assignee of this invention.

The discharge device 1 may be held rigidly in the position illustrated by using a construction which comprises a cylinder 31 which telescopes cylinder 27 at one end thereof. Cylinder 31 is provided with a threaded collar 32 to engage threads upon a portion of the outer surface of cylinder 27. A metallic ring 33 is closely fitted to, or may be formed integral with, cylinder 31 and constitute a means for supporting socket 34 for discharge device 1 in position, and hence serves as a means for rigidly supporting the discharge device 1 in firm engagement with members 28 and 29.

In order to connect cylinder 25 to anode 2, and more particularly to the part 24 thereof, I may employ a metallic adapter 35 which is, of course, conductively connected to cylinder 25. This adapter may be constructed of a solid metal such as brass or copper and be provided with a recess to receive the enlarged section 24 of the anode construction.

I provide means for tuning the space resonant regions. One of these tuning means may be associated with the anode-grid region and may comprise a piston 36 which is in engagement with and slideable along the outer surface of cylinder 25 and the inner surface of cylinder 26 and may

5 be actuated by suitable means such as an actuating rod 37. In like manner, the grid-cathode region may be tuned by a piston 38 which is in engagement with and slideable along the outer surface of cylinder 26 and the inner surface of cylinder 27. Actuating rods 39 may also be employed as a mechanical expedient for positioning the piston 38.

To apply unidirectional potential to the anode-grid circuit of the discharge device 1, the anode 2 and more particularly the part 24 thereof may be connected to a source of unidirectional potential by means of a cylindrical conductor 40 which is positioned within cylinder 25 and which is connected to adapter 35. Of course, the negative terminal of the unidirectional source is connected to contact pins 17 or 18 of the discharge device through either terminal 40' or 41 of socket 34.

Energy may be derived from the anode-grid region of the system by employing output electrode means which may comprise a loop 42 constituting an extension of an inner conductor 43 of a concentric transmission line 44. Of course, it is to be appreciated that other forms of electrode means may be employed for extracting energy from the space resonant system.

I provide within the cylinder 26 which defines the common boundary between the anode-grid and grid-cathode space resonant regions, an opening 45 having an appreciable axial or longitudinal dimension to afford sufficient coupling between these regions throughout a substantial range of the operating frequency of the system. This opening, which may have a configuration generally described as a narrow spiral or helical slot, is preferably positioned within the vicinity of the maximum of the standing potential wave in the anode-grid region.

I have found that in space resonant systems 40 which may be operated as coaxial wave propagating systems having wave lengths which are odd multiples of quarter wave lengths, such as three-quarters or five quarters wave lengths, there are certain phase reversals which occur 45 inside the lines or the region defined by the conductive members in such a way that the cathode and anode potentials of the discharge device are brought geometrically close to each other on opposite sides of the member which defines the common boundary between the two regions. The existence of this phenomenon is, of course, due to the self-shielding characteristics of the respective coaxial lines. More particularly, it is due to the thin penetration depth of the current 50 which permits the existence of two individual and relatively independent currents on opposite sides of the same piece of metal defining the common boundary between the two regions. Consequently, the above described coupling slot 45 is employed to supply the feed back connection required. The slot 45 when placed at the proper position permits the flow of energy from one side of cylinder 26 to the other side, thereby exciting the grid-cathode region at the proper position to obtain the desired phase relationship between the respective electrode voltages of the discharge device. It will be appreciated that there are a number of places or points at which such a coupling slot may be located, the number of course depending upon the electrical length of the space resonant regions under consideration.

In accordance with another feature of my invention, cylinder 26 may be provided with another opening 45' diametrically opposed to opening 45. The two openings may operate in conjunction, or

separately, as coupling means between the anode-grid and the grid-cathode space resonant regions. Opening 45 is also preferably of spiral or helical configuration having a relatively narrow width, and may be designed to have a curvature opposite to that of opening 45 with respect to the axial dimension of the space resonant regions.

The general features of operation of the space resonant system shown in Fig. 1 will now be briefly reviewed. Upon the application of a unidirectional potential to the anode and cathode of discharge device 1, the system will oscillate. Energy may be derived from the anode-grid region through the concentric transmission line 44 and supplied to an external or utilization circuit. The grid-cathode region is maintained in oscillation through the energy supplied thereto from the anode-grid cavity through opening 45 or 45', or both, which constitute the coupling means.

By virtue of the fact that the opening 45 or 45' has an appreciable axial length, it should be appreciated that this feature permits substantial adjustment of the operating frequency of the system without materially changing the coupling between the anode-grid and the grid-cathode regions, thereby dispensing with the necessity of adjustable coupling means or devices. By positioning openings 45 and 45' within the vicinity of the voltage maximum of the standing electromagnetic wave within the anode-grid region, sufficient coupling is provided throughout a range determined by the effective axial dimension of the openings.

The relation of the position of openings 45 and 45' with respect to the voltage and current standing waves within the anode-grid region may be more fully appreciated by referring to Fig. 3 which represents in simplified form the anode-grid region defined by cylinders 26 and 27 and plunger 36 and which may be considered as constituting, for the purposes of analysis, a tuned three-quarter wave length coaxial line having a physical length compensated for end-effects, and establishing standing voltage and current waves A and B, respectively. Upon adjustment of the operating frequency of the system, it will be appreciated that the voltage maximum of the standing wave within the anode-grid region will change in position. However, due to the helical shape of the openings 45 and 45' the effect of such a change in position of the voltage maximum does not change the coupling between the anode-grid and grid-cathode regions and consequently permits adjustment of the operating frequency without entailing a loss of output power.

While in the above description of my invention I have chosen to describe its operation with particular reference to an oscillator, it will be understood by those skilled in the art that it may be applied to space resonant systems generally where it is desired to couple a pair or plurality of space resonant regions.

While I have shown and described my invention as applied to a particular system and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. A high frequency space resonant system comprising a plurality of space resonant regions

defined by a pair of outer conductive members and an intermediate conductive member, said intermediate conductive member being provided with an opening located within the vicinity of the potential maximum of the standing electromagnetic wave within one of said regions, said opening having both longitudinal and lateral progression along the surface of said intermediate member, and means for exciting said one of said regions.

2. A high frequency space resonant system comprising a plurality of space resonant regions defined by a plurality of cylindrical conductive members, the intermediate member defining the common boundary between the space resonant regions being provided with a slot located within the vicinity of the potential maximum of the standing electromagnetic wave within one of said regions and constituting coupling means between the regions, said slot having both longitudinal and tangential progression along the axis of said intermediate member, and means for establishing an electromagnetic wave within one of said regions.

3. A high frequency space resonant system comprising a pair of space resonant regions defined by a plurality of concentric conductive cylinders, means for establishing an electromagnetic wave within one of said regions, the intermediate cylinder defining the common boundary between said regions being provided with a pair of oppositely disposed slots located within the vicinity of the potential maximum of the standing electromagnetic wave within said one region said slots having both longitudinal and tangential progression along the axis of said intermediate cylinder.

4. A high frequency space resonant system comprising a plurality of space resonant regions defined by a pair of outer conductive members and an intermediate conductive member, means for establishing an electromagnetic wave within one of said regions, and means for controlling the operating frequency of said space resonant system, said intermediate conductive member being provided with a helical opening located within the vicinity of the potential maximum of the standing electromagnetic wave within one of said regions thereby constituting a coupling path between said regions effective throughout a predetermined range of operating frequencies.

5. A high frequency space resonant system comprising a plurality of space resonant regions defined by a pair of outer conductive members and an intermediate conductive member, means for establishing an electromagnetic wave within one of said regions, means for controlling the operating frequency of said system, said intermediate member being provided with a helical opening located within the vicinity of the potential maximum of the standing electromagnetic wave within said one region and having an appreciable axial dimension thereby constituting coupling means substantially independent of the operating frequency.

6. A high frequency space resonant system comprising an electric discharge device including a plurality of enclosed electrodes including an anode, a cathode and a grid, a plurality of conductive members connected to said electrodes to form anode-grid and grid-cathode space resonant regions, one of said members being provided with an opening having an appreciable axial length and tangential progression to form a communicating path between said anode-grid and said grid-cathode regions located within the vicin-

ity of the maximum of the anode-grid region standing potential wave to afford substantial coupling between said regions throughout an appreciable range of operating frequencies of said system.

7. A high frequency space resonant system comprising an electric discharge device including a plurality of enclosed electrodes including an anode, a cathode and a grid, and a plurality of substantially concentric members connected respectively to said electrodes and defining anode-grid and grid-cathode space resonant regions, the intermediate member connected to said grid being provided with an opening located within the vicinity of the potential maximum of the standing electromagnetic wave of said anode-grid region and having appreciable axial length to afford substantial coupling between said regions throughout the range of operating frequencies of said system.

8. A high frequency space resonant system comprising an electric discharge device including a plurality of enclosed electrodes including an anode, a cathode and a grid, and a plurality of substantially concentric members connected respectively to said electrodes and defining anode-grid and grid-cathode space resonant regions, the intermediate member being provided with a helical opening constituting a communicating path between said regions.

9. A high frequency space resonant system comprising an electric discharge device having a plurality of enclosed electrodes including an anode, a cathode and a grid and high frequency terminals therefor, three concentric conductive cylinders connected respectively to the terminals for said electrodes for defining anode-grid and grid-cathode space resonant regions, means for tuning at least one of said regions, the intermediate cylinder connected to said grid being provided with an opening constituting a communicating path between said regions and having a substantial axial dimension to afford sufficient coupling throughout a range of operating frequencies of said system.

10. A high frequency space resonant system comprising an electric discharge device including a plurality of enclosed electrodes including an anode, a cathode and a grid, a plurality of substantially concentric conductive members connected respectively to said electrodes and defining anode-grid and grid-cathode space resonant regions, the intermediate member being provided with a helical opening constituting a communicating path between regions, and means for tuning at least one of said regions.

11. A high frequency space resonant system comprising an electric discharge device including a plurality of enclosed electrodes including an anode, a cathode and a grid, a plurality of conductive members connected to said electrodes to form anode-grid and grid-cathode space resonant regions, the member connected to said grid being provided with a narrow helical slot located within the vicinity of the maximum of the anode-grid region standing potential wave, and means for tuning at least one of said regions.

12. A high frequency space resonant system

comprising an electric discharge device including a plurality of enclosed electrodes including an anode, a cathode and a grid, a plurality of substantially concentric conductive members connected respectively to said electrodes and defining anode-grid and grid-cathode space resonant regions, the intermediate member connected to said grid being provided with a pair of opposed openings located within the vicinity of the potential maximum of the standing electromagnetic wave of said anode-grid region and constituting coupling means between the anode-grid and the grid-cathode space resonant regions.

13. A high frequency space resonant system comprising an electric discharge device including a plurality of enclosed electrodes including an anode, a cathode and a grid, a plurality of cylindrical conductive members connected to said electrodes to form anode-grid and grid-cathode space resonant regions, and a pair of diametrically opposed coupling paths in the cylinder defining the common boundary between the anode-grid and the grid-cathode space resonant regions, said cylinder being provided with helical slots to form said paths.

14. A high frequency space resonant system comprising an electric discharge device including a plurality of enclosed electrodes including an anode, a cathode and a grid, a plurality of substantially concentric conductive cylinders connected respectively to said electrodes and defining anode-grid and grid-cathode space resonant regions, the intermediate cylinder connected to said grid being provided with a pair of diametrically opposed and longitudinally and tangentially progressively slots located within the vicinity of the potential maximum of the standing electromagnetic wave of said anode-grid region thereby constituting coupling means between the anode-grid and the grid-cathode space resonant regions.

15. A high frequency space resonant system comprising an electric discharge device including a plurality of enclosed electrodes including an anode, a cathode and a grid, a plurality of substantially concentric conductive members connected respectively to said electrodes and defining anode-grid and grid-cathode space resonant regions, the intermediate member connected to said grid being provided with a pair of slots having reverse curvatures relative to the longitudinal axis of said regions thereby constituting coupling means between the anode-grid and the grid-cathode space resonant regions.
